UNITED STATES PATENT OFFICE.

CHARLES V. JAMESON, OF CHICAGO, ILLINOIS.

TAKE-UP SPOOL FOR MUSIC-SHEETS.

1,307,257.

Specification of Letters Patent. Patented June 17, 1919.

Application filed August 22, 1917. Serial No. 187,683.

To all whom it may concern:

Be it known that I, CHARLES V. JAMESON, a citizen of the United States, residing at Chicago, in the county of Cook and State of

5 Illinois, have invented new and useful Improvements in Take-Up Spools for Music-Sheets, of which the following is a specification.

This invention relates to the spools upon 10 which the music sheets of automatic musical instruments are wound, and more particularly to the take-up spools.

Heretofore, such spools have been provided at one end with a stationary head or flange and 15 at the other end with a spring-pressed flange intended to compensate for variations in the widths of different music sheets as well as shift the sheet against the face of the stationary flange to cause it to track properly, 20 the stationary flange being located at a predetermined distance from the adjacent wall of the tracker-box for that purpose. The yieldable flange is formed in one piece and therefore bodily movable with relation to the 25 opposite flange. This construction is unsatisfactory, it being found in practice that if the spring of the movable flange is light enough to avoid binding or fraying of the edges of the music-sheet, it is not strong 30 enough to shift the sheet against the stationary flange.

It is the object of my invention to provide a spool of this character which accurately and reliably guides the music sheet and yet 35 exerts so gentle a lateral pressure against it as to leave its edges smooth and intact.

In the accompanying drawings:

Figure 1 is a front elevation of a tracker box equipped with the improved spool. 40 Fig. 2 is an enlarged cross section thereof in connection with a music sheet and a tracker. Fig. 3 is a fragmentary sectional elevation of the spool on a further enlarged scale. Fig. 4 is an end view of the spool, omitting 45 the spring of one of the flange-segments. Fig. 5 is a side elevation of a modified construction of the spool.

Similar characters of reference indicate corresponding parts throughout the several 50 views.

1 indicates the tracker box or frame, 2 the music spool, 3 the take-up spool and 4 the tracker board. In the drawings, the improvement is shown in connection with the 55 take-up spool, but it is equally applicable to

the music spool and other sheet-guiding spools or rollers.

At one end the take-up spool is preferably provided with the customary stationary head or flange 5 arranged in the usual predetermined relation to the adjacent wall of the tracker box or the row of ducts in the tracker-board. At its opposite end the spool carries a head or flange coöperating with the fixed flange 5 and composed of a plurality of yieldable or spring-pressed sections 6 movable toward and from the fixed flange and tending constantly to shift the music sheet against the same to insure its proper tracking. The yieldable flange is also adapted to accommodate itself to any imperfections or dimensional variations of the music sheets due to climatic influences or other causes. In its preferred form the yieldable flange comprises a circular series of radial segments or sectors movable lengthwise of the spool, independently of one another, and each having an individual spring 7 for pressing it inwardly or toward the fixed flange. In the embodiment of the invention shown in the drawings, the segments are arranged to swing lengthwise of the spool, and for this purpose each segment is pivotally attached thereto by a headed pin or nail 8 driven into the end of the spool and passing loosely through an opening 9 in the inner portion of the segment. Between its ends each segment is provided with a radial slot or opening 10 through which passes a guide pin or screw 11 projecting from the end of the spool. The springs 7 are applied to these guide screws between their heads and the outer sides of the segments. The springs are preferably of the conical or volute type and their bases are countersunk in circular recesses 12 in the segments, as shown in Fig. 3. Other kinds of springs may be employed if desired, but I prefer those shown, on account of their neatness and compactness and their uniform bearing against the segments on all sides of the guide screws 11.

In the use of the improved take-up spool, if the traveling music sheet on approaching the spool is more or less out of its true tracking course, it is restored to its central position by the action of the spring-pressed segments which successively engage the edge of the sheet and gently and gradually shift it toward and against the face of the fixed spool-flange 5. This restoring action of the 110

sheet takes place whenever it tends to swerve from its proper course.

To facilitate this action, the flange-segments preferably are normally arranged in an inwardly tilted position, as shown in Fig. 3. They may be caused to assume this position by any suitable means. The devices shown in the drawings for this purpose consist of collars or washers 13 mounted on the pivot-pins 8 between the straight end of the spool and the inner portions of the segments.

By employing such a sectional or segmental spool-flange in connection with individual springs for the segments, the springs may be made so light that the pressure of the segments will not fray or displace the edges of the music sheets. At the same time, the springs are sufficiently powerful to center the sheet when displaced, inasmuch as the segments do not operate simultaneously but act successively upon the sheet, shifting it gradually by a number of light taps or impulses.

Instead of making one of the spool flanges stationary, both flanges may be yieldable or spring-pressed, if desired, as shown in Fig. 5. In this case both flanges operate to center the sheet.

I claim as my invention:

1. A spool for a music sheet having an end-flange composed of a plurality of yieldable portions.
2. A spool for a music sheet having an end-flange comprising a series of independently yieldable portions constructed and arranged to exert successive impulses against the edge of the music sheet.

Copies of this patent may be obtained for five cents each, by addressing the "Commissioner of Patents, Washington, D. C."

3. A spool for a music sheet having an end-flange composed of independently movable spring-pressed portions. 40

4. A spool for a music sheet having an end-flange composed of radial segments yieldable independently of one another, lengthwise of the spool. 45

5. A spool for a music sheet having an end-flange composed of independent radial segments, and springs for pressing the segments inwardly.

6. A spool for a music sheet having an end-flange composed of radial segments pivotally attached to the end of the spool to swing lengthwise thereof, and springs for pressing the segments inwardly. 50

7. A spool for a music sheet having an end-flange composed of independent radial segments pivotally attached to the end of the spool to swing lengthwise thereof, each segment having an opening between its ends, guide pins projecting from the end of the spool and through said openings, and springs mounted on said pins and bearing against the outer sides of the segments. 55

8. A spool for a music sheet having an end-flange composed of yieldable radial segments normally tilted inwardly. 60 65

9. A spool for a music sheet provided with an end-flange composed of radial segments having their inner portions pivotally attached to the end of the spool, washers 70 interposed between said inner portions and the end of the spool to tilt the segments inwardly, and springs bearing against the outer sides of the segments.

CHARLES V. JAMESON.
